DESIGN FOR A CABINET FOR CARD GAME PARAPHERNALIA

Julius G. Forstmann, New York, N. Y.

Application November 24, 1937, Serial No. 73,171

Term of patent 3½ years

To all whom it may concern:

Be it known that I, Julius G. Forstmann, a citizen of the United States, residing at 520 East 86th Street, in the county of New York and State of New York, have invented a new, original, and ornamental Design for a Cabinet for Card Game Paraphernalia, of which the following is a specification, reference being had to the accompanying drawing, forming part thereof.

In the drawing:

The reference character 1 represents the case and the reference character 2 represents the drawer.

I claim:

The ornamental design for a cabinet for card game paraphernalia, as shown and described.

JULIUS G. FORSTMANN.
